(57) **CLAIM**

We claim the ornamental design for a handle of a dental light, as shown and described.

DESCRIPTION

FIG. 1 is a perspective view of a handle of a dental light.
FIG. 2 is a rear side perspective view of the dental light of FIG. 1.

FIG. 3 is a side view of the left side of the dental light of FIG. 1, the right side of the dental light being a mirror image thereof.

FIG. 4 is a top side view of the dental light of FIG. 1.

FIG. 5 is a front side view of the dental light of FIG. 1; and, FIG. 6 is a bottom side view of the dental light of FIG. 1.

The broken lines shown herein are for illustrating portions of the dental light and environment only and form no part of the claimed design.
